UNITED STATES PATENT OFFICE.

ARTHUR DUDLEY SOUTHAM AND HORACE CUTHBERT HIDES, OF HARTFORD, CONNECTICUT.

ILLUMINATING-MIRROR.

No. 856,497.

Specification of Letters Patent.

Patented June 11, 1907.

Application filed December 21, 1905. Serial No. 292,699.

To all whom it may concern:

Be it known that we, ARTHUR DUDLEY SOUTHAM and HORACE CUTHBERT HIDES, citizens of the United States, residing at 5 Hartford, in the county of Hartford, State of Connecticut, have invented certain new and useful Improvements in Illuminating-Mirrors, of which the following is a specification, reference being had therein to the accompanying drawing, in which,

Figure 1 is a front view of a hand mirror provided with our invention; Fig. 2 a vertical sectional view thereof taken approximately on the line II—II of Fig. 1; and Fig. 3 15 a vertical sectional view of a slightly different form of the device.

The invention relates to mirrors in general, but is more particularly suitable for small hand mirrors.

20 One of the main objects of the invention is to so construct a mirror that the object reflected therein will be illuminated so that the reflection will be more clear and distinct.

Referring to the various parts by numerals, 1 designates the mirror frame; 2 the glass which is silvered on the back as indicated at 25 3 in Fig. 2. Back of the glass 2 is formed a chamber 4, entrance to which is preferably had by a hinged door 5, said door being held

30 in its closed position by means of a catch 6. The glass is formed in its opposite side edges with openings 7, and within the chamber 4 in the rear of each of these openings is arranged a small incandescent electric lamp bulb 8. These lamps are in a circuit 9, the wires of 35 which pass out through the handle 1^a of the mirror and through a connection plug 10 detachably secured to the end of the handle.

Arranged in this circuit are two contacts 11 40 which are normally disconnected so that the lamp circuit is normally open. These contacts are adapted to be brought together by means of a push-button 12 whenever it is desired to light the lamps 8. It will, of course,

45 be understood, that if desired this contact device may be dispensed with and the circuit made permanently closed. The lamps may be supplied with current from any suitable source of supply, either a separate battery or 50 from an ordinary house lighting circuit. Supported in the rear of the lamps is a reflector 5^c. As shown in Figs. 2 and 3 this reflector is the concave inner side of the doors 5 and 5^a which may be polished or sil-

vered as desired. It is obvious that any 55 suitable form of reflector may be arranged in the rear of the lamps and the said reflector may be supported in any suitable manner.

In Fig. 3 a small dry battery 13 is shown as arranged in the handle 1^b of the mirror, 60 and a contact device 12^a is provided by which the lamps may be lighted when desired. Entrance to the chamber 4^a is had through a hinged door 5^a, this door being secured in its closed position by means of a catch 6^a. In 65 this form of the device the openings through the glass are dispensed with, and instead, the silver 3^a on the back of the mirror glass is omitted adjacent the lamps, as shown at 3^b in Fig. 3, so that the light of the lamps will 70 pass through said unsilvered part of the glass. A series of small holes 6^b may be located at the back of the casing to allow the heat from the lamps to escape, as shown in Fig. 3. When desired the battery 13 may be 75 removed from the handle of the mirror by unscrewing cap 14.

While we have shown the battery as arranged in the handle part of the mirror in Fig. 3, we desire it understood that this is 80 done merely for the purpose of illustration. It is, of course, obvious that the battery may be arranged in any part of the mirror frame and that the batteries may be made in any shape desired and that any number of them 85 may be placed in the frame to produce the desired results. It will, of course, be understood, that the lamps must be of very small candle power in order that we may place in the mirror frame sufficient battery power to 90 light them.

From the foregoing it will be readily understood that we provide a very simple, convenient and effective illuminating hand mirror which is especially adapted for ladies' use, 95 as it will greatly assist them in viewing and illuminating their back hair.

By means of the contact devices the lamps need only be lighted when the mirror is in use. At other times the circuits are broken, 100 thereby preventing the exhaustion of the lamps and the batteries.

It is obvious that the size, shape and design of the mirror and of the lamps may be varied in many respects and to almost any 105 extent, and we, therefore, wish it understood that we are not to be limited to the construction shown and described.

Having thus described our invention, what we claim as new and desire to secure by Letters Patent, is:—

1. An illuminating mirror comprising an opaque mirror glass, a frame for said glass, a lamp chamber formed in the rear of said glass, said glass forming an opaque closure for the greater portion of said chamber and being adapted to prevent the passage of light rays therethrough except at certain points at the side edges thereof, an electric lamp supported in said chamber, circuit wires connected to said lamp, a battery arranged in the frame and connected to the circuit wires, and means for making and breaking the circuit through said wires.
2. An illuminating mirror comprising a mirror glass, a frame for said glass said glass being opaque to prevent the passage of light rays, except at certain points within the frame, a handle part connected to said frame, a lamp chamber, an electric lamp supported in said chamber, circuit wires connected to said lamp, and means for making and breaking the circuit.
3. An illuminating mirror comprising a mirror glass, a frame for said glass, a handle part connected to said frame, a lamp chamber formed in said frame, an electric lamp supported in said chamber, circuit wires connected to said lamp, means for making and breaking the circuit, and a battery arranged in the frame and connected to the circuit wires, a part of the mirror glass being unsilvered to permit the light from the lamp to pass through said glass, the mirror glass being otherwise opaque to prevent the passage of light rays.
4. An illuminating mirror comprising a mirror glass opaque throughout except at two points on opposite edges thereof, a frame for said glass, a lamp chamber formed in said frame in the rear of the mirror glass, electric lamps supported in said chamber, circuit wires connected to said lamps, means for making and breaking said circuit, and a reflector back of said lamps and adapted to throw the light forward through the mirror glass at opposite edges thereof.
5. An illuminating mirror comprising a mirror glass opaque throughout except at two points on opposite edges thereof, said glass being transparent at said two points, a frame for said glass, a lamp chamber formed in said frame in the rear of the mirror glass, electric lamps supported in said chamber, one of said lamps being in the rear of each transparent portion of the mirror glass, circuit wires connected to said lamps, means for making and breaking the circuit, and a reflector back of said lamps and adapted to throw the light forward through the transparent portions of the mirror glass.
6. An illuminating mirror comprising a

mirror glass opaque throughout except at two points on opposite edges thereof, said glass being transparent at said two points, a frame for said glass and provided with a handle, a lamp chamber formed in said frame in the rear of the mirror glass, electric lamps supported in said chamber, one of said lamps being in the rear of each transparent portion of the mirror glass, circuit wires connected to said lamps, means within the handle for making and breaking the circuit, and a reflector back of said lamps and adapted to throw the light forward through the transparent portions of the mirror glass.

7. An illuminating mirror comprising a mirror glass, a frame for said glass, a handle part connected to said frame, a lamp chamber formed in said frame, the rear wall of said chamber being formed by a hinged plate concave on its inner side and adapted to act as a reflector, said mirror glass forming an opaque closure for the greater portion of said chamber and being adapted to prevent the passage of light rays therethrough, except at certain points at the side edges thereof, an electric lamp or lamps supported in said chamber, circuit wires connected to said lamp or lamps, and means for making and breaking the circuit.

8. An illuminating mirror comprising a mirror glass, a frame for said glass, a handle connected to said frame, a lamp chamber formed in said frame, the rear wall of said chamber being concave on its inner side and adapted to act as a reflector, said mirror glass forming an opaque closure for the greater portion of said chamber and being adapted to prevent the passage of light rays therethrough, except at certain points at the side edges thereof, an electric lamp supported in said chamber, circuit wires connected to said lamp, and means for making and breaking the circuit.

9. An illuminating mirror comprising a mirror glass, a frame for said glass, a handle connected to said frame, a lamp chamber being formed in said frame in the rear of the glass, said mirror glass forming an opaque closure for the greater portion of said chamber and being adapted to prevent the passage of light rays therethrough except at certain points at the side edges thereof, an electric lamp supported in said chamber, circuit wires connected to said lamp, and means for making and breaking the circuit.

In testimony whereof we hereunto affix our signatures in the presence of two witnesses this 2nd day of December 1905.

ARTHUR DUDLEY SOUTHAM.
HORACE CUTHBERT HIDES.
